UNITED STATES PATENT OFFICE.

JACOB L. BAUER, OF MILWAUKEE, WISCONSIN.

LIFTING DEVICE FOR PHONOGRAPH DISKS.

1,426,034.

Specification of Letters Patent. Patented Aug. 15, 1922.

Application filed July 20, 1920. Serial No. 397,594.

To all whom it may concern:

Be it known that I, JACOB L. BAUER, a citizen of the United States, and resident of Milwaukee, in the county of Milwaukee and

5 State of Wisconsin, have invented certain new and useful Improvements in Lifting Devices for Phonograph Disks; and I do hereby declare that the following is a full, clear, and exact description thereof.

10 This invention relates to improvements in phonograph turn tables and has primarily for its object the provision of a device adapted to lift or raise the record from the table, thereby enabling the operator to more conveniently grasp the record when its removal is desired.

15 Another object resides in the provision of a device of this character adapted to be operated from a stationary point regardless of 20 the position in which the turn table mechanism might come to rest.

In the accompanying drawings,

Figure 1 is a plan view of a phonograph turn table, with parts broken away to more 25 clearly illustrate the invention, and

Figure 2 is a sectional view indicated on the line 2—2 of Figure 1.

At the present time considerable difficulty 30 is often encountered in removing a record disc from the turn table, inasmuch as the records are very thin and it is necessary to get under the same in order to obtain a sufficient hold. In order to overcome this, the present device has been designed in which a 35 phonograph turn table T having the usual central depression D and a felt or cloth covering C is provided with a record engaging device 1. This device comprises a circular plate 2, positioned below the turn table, and 40 provided with an opening 2' to permit the same to surround the motor shaft S. Secured to the plate 2 and extending through the depressed portion D of the turn table are studs or projections 3 provided with retaining heads 3', which under normal conditions, 45 will support the plate 2 in a horizontal position. It will be noted that the heads 3' when in a normal position will be disposed below the surface, of the turn table, upon which 50 the record disk R, shown in dotted lines, will rest.

Secured to the cabinet C in a suitable position is a bracket 4 which carries a rock lever 5. One end of the lever that extends outwardly of the turn table is provided with a manipulating handle 6 while the opposite end is shaped to form a crank 7 positioned

directly beneath one portion of the circular plate 2. The weight of the crank portion 7 will normally cause the same to rest upon 60 the cabinet out of engagement with the circular plate while the manipulating handle 6 will be slightly inclined upwardly. It will thus be seen that upon exerting pressure on the actuating handle 6 the lever 5 will be 65 rocked, causing the crank 7 to engage and lift or tilt the plate 2, which operation will cause the studs or projections 3 to engage and lift one side of the record disk R as shown in dotted lines upon Figure 2. Cover plate may 70 be bulged, as shown in Figure 2, or a felt of sufficient elasticity may be provided to permit a lifting action by posts 3. For convenience the manipulating handle 6 is shown positioned at the right side of the turn table, 75 while the crank 7 is adapted to raise or tilt the circular plate at the left side which enables the operator to remove the record with the one hand while operating the lifting mechanism.

80 From the foregoing description taken in connection with the drawings, it will be noted that a very simple and efficient device has been provided which can be operated from a stationary point, regardless of the 85 position in which the turntable might come to rest.

It will further be seen that because of the depression provided in the turn table and the felt or cloth covering, all of which are standard construction, the present device can be attached to a turn table without in any way affecting its appearance.

I claim:

1. The combination of a phonograph turn 95 table, a plate carried thereby, and means adapted to raise said plate by contact therewith at one point so as to tilt the plate and exercise a tilting action on a record.

2. The combination of a phonograph turn 110 table, a plate rotatable therewith, means on said plate for lifting a record, an elongated cylindrical rod and an arm at each end of said rod, said arms extending at an angle to said rod and in different planes, a bearing 105 supporting said rod and permitting rotation thereof so that manual tilting one arm moves the other arm to raise said plate and lift said record.

In testimony that I claim the foregoing I 110 have hereunto set my hand at Milwaukee, in the county of Milwaukee and State of Wisconsin.

JACOB L. BAUER.
